UNITED STATES PATENT OFFICE.

BERNE NADALL, OF CHICAGO, ILLINOIS, AND GUSTAVE A. BARNES, OF LONDON, ENGLAND, ASSIGNORS TO THE LINOTYPE COMPANY, LIMITED, OF LONDON, ENGLAND.

DESIGN FOR A FONT OF LOWER-CASE PRINTING-TYPE.

SPECIFICATION forming part of Design No. 36,017, dated August 19, 1902.

Application filed July 17, 1902. Serial No. 116,006. Term of patent 14 years.

To all whom it may concern:

Be it known that we, BERNE NADALL, a citizen of the United States, residing at Chicago, in the county of Cook and State of Illinois, and 5 GUSTAVE ADRIAN BARNES, a subject of the King of England, residing at London, England, have invented and produced a new, original, and ornamental Design for a Font of Lower-Case Printing-Type, of which the following is 10 a specification.

Our new and original design for a font of lower-case printing-type is illustrated in the accompanying drawing.

Some of the distinguishing features or characteristics of the type composing the font will 15 be hereinafter described by reference to said drawing.

The lower end of the perpendicular of the letter b is cut away or reduced on its right-hand side, thus providing a sharp triangular point projecting below and to the left of the curved body of said letter. The curved line forming said body is reduced in thickness toward both points of its connection with said 20 perpendicular, and the upper end of said perpendicular is deflected slightly toward the left, the face or upper surface of said end being a horizontal line.

The ends of the perpendicular of the letter d are deflected slightly in opposite directions, the upper end being deflected slightly toward the left and the lower end toward the right. The lower end is of such form as to provide 25 a sharp-pointed projection, while the upper end is a horizontal line.

The upper curved end of the letter f is reduced in thickness and has but a slight curve, and the cross-line of said letter is arranged relatively near said upper curved end.

The lower end of the left-hand line of the letter h is enlarged to provide a foot or base, and the lower end of the right-hand curved line of said letter is provided with a terminal extending slightly toward the right. This 30 curved line is varied in thickness throughout its length.

The upper faces of the letters i and j are

inclined upwardly from left to right, and the lower faces of the dots above them have a corresponding inclination. The upper end of the perpendicular of the letter i is enlarged, projecting slightly beyond both sides of said perpendicular, while the upper end of the letter j is projected slightly toward the right. The lower end of this letter is tapered and deflected 55 toward the left.

The letter l is increased slightly in width at its upper end, so as to project beyond both faces of the perpendicular body portion thereof, while its lower end is projected to the left 60 of said body portion only. The upper end of the perpendicular of the letter t is curved to the left and the cross-line of said letter intersects the perpendicular at the lower end of said curve. The lower end of this letter is 65 deflected sharply to the right, forming a substantially horizontal pointed section.

The left-hand curved line of the letter u has a sharp angular projection extending to the left of its upper free end, and the upper end 70 of the right-hand line of said letter has a somewhat similar, but less pronounced, projection. The lower end of said right-hand line projects sharply toward the right.

The letter v is formed by two curved lines, 75 the left-hand one of which is of substantially the same width throughout its length, while the lower portion of the right-hand line is considerably thinner than the upper portion thereof. The upper ends of both of said lines 80 are horizontal.

The letter w is formed by two relatively heavy and substantially straight inclined lines and two thinner curved lines. The upper end of the right-hand curved line is 85 slightly enlarged.

The right-hand line of the letter y is reduced in thickness from both ends toward the center, and the left-hand line, which is curved slightly throughout its length and is relatively 90 heavier than the right-hand line, is connected to said reduced portion of the right-hand line.

The perpendicular, forming the right-hand line of the letter a of the diphthong æ, pro-

jects below both of the curved lines of the letters of said diphthong.

Having thus described our invention, what we claim, and desire to secure by Letters Patent, is—

The ornamental design for a font of lower-case printing-type substantially as herein shown and described.

In testimony whereof we affix our signatures in presence of two witnesses.

BERNE NADALL.

GUSTAVE A. BARNES.
